187,629

LETTER OPENER OR A SIMILAR ARTICLE

Dmitry Dolgorukov and Gregory Dolgorukov, Jr.,
Ferndale, Mich.

Application April 1, 1959, Serial No. 55,311

Term of patent 14 years

(Cl. D74—1)

Fig. 1 is a plan view of a letter opener embodying our new design, the side opposite thereto being identical in appearance;

Fig. 2 is a sectional view taken on the line 2—2 of Fig. 1; and

Fig. 3 is a sectional view thereof taken on the line 3—3 of Fig. 1.

We claim:

The ornamental design for a letter opener or a similar article, as shown and described.

References Cited in the file of this patent

UNITED STATES PATENTS

D. 136,445	Gerber	Oct. 5, 1943
D. 141,315	Simeone	May 22, 1945
D. 141,875	Goldbert	July 31, 1945